[57] **ABSTRACT**

A trailer cap forming a closure between the roof and front end wall of a trailer of the type having a curved front end wall and a curved or bowed roof in which the cap is formed by a male and female die in a metal press.

TRAILER CAP AND METHOD OF FORMING SAME**BACKGROUND OF THE INVENTION****1. Field of the Invention**

The present invention generally relates to a metal trailer cap which joins the front end wall to the roof of trailers and more particularly a method of forming such end caps by utilizing a metal press.

2. Description of the Prior Art

Trailer caps constructed of sheet metal have been used where an arcuately curved front end wall is joined to the forward end of the roof of a trailer. U.S. Pat. No. 3,389,670 discloses a trailer cap and discusses the conventional technique of employing a plurality of triangular segments or gores which are joined together by welding or the like. This prior patent also discloses a technique in which the sheet metal is formed by utilizing a spinning technique. While such spinning technique is employed, the limitations inherent in the spinning technique limit the shapes and configurations that can be formed and also require considerable expenditure of time and labor in forming the end cap. As set forth in that patent, the material and labor costs involved adversely affect the manufacturing cost of the trailer end cap.

SUMMARY OF THE INVENTION

An object of the invention is to provide a trailer end cap of sheet metal formed by a male and female die in a press utilizing a rectangular piece of sheet metal stock to form two end caps which are joined together and are subsequently cut apart by a correspondingly shaped die cutter and also trimmed peripherally to form two end caps from the single sheet of material.

Another object of the invention is to provide a trailer end cap of sheet metal formed by a sheet metal press having shape limitations corresponding with the limitations of the sheet metal being employed to enable the rapid formation of two trailer end caps from a single rectangular sheet of sheet metal.

These together with other objects and advantages which will become subsequently apparent reside in the details of construction and operation as more fully hereinafter described and claimed, reference being had to the accompanying drawings forming a part hereof, wherein like numerals refer to like parts throughout.

BRIEF DESCRIPTION OF THE DRAWINGS

FIG. 1 is a schematic perspective view of a trailer employing the end cap of the present invention therein.

FIG. 2 is a perspective view of the end cap.

FIG. 3 is a plan view of the product after it has been deformed from a sheet panel into an intermediate structure.

FIG. 4 is a side elevational view of the intermediate structure of FIG. 3.

DESCRIPTION OF THE PREFERRED EMBODIMENT

Referring now specifically to the drawings, a horse trailer is generally designated by numeral 10 in FIG. 1 which may be of conventional construction and includes supporting wheels 12, side walls 14, a towing tongue 16, an arcuately curved front end wall 18 and a roof 20 and an end cap generally designated by the numeral 22 which incorporates the present invention

therein in which the peripheral edges of the end cap 22 are connected to the front end wall 18 and the roof 20 by conventional joining techniques.

The end cap 22 is constructed of sheet metal and includes a top or roof portion 24 that is in alignment with the roof 20 with the forward and side edge portions of the end cap being downwardly curved at 26 and also arcuate in configuration when observed from the top or bottom. The rearward edge of the end cap is straight as designated by numeral 28.

The curved peripheral edge 26 may be curved as part of a circle or may be semi-elliptical in configuration. When a semi-elliptical construction is desired, the dimensions of the major and minor axes of the ellipse may vary.

In forming the end cap, a rectangular sheet of sheet metal 30 is utilized and the corners thereof are cut off as indicated at 32 in FIG. 3. The sheet metal used is a deep draw, aluminum kill sheet steel that is manufactured by Republic Steel Co. The intermediate product illustrated in FIGS. 3 and 4 and designated by numeral 34 is formed in a sheet metal press capable of exerting a 1,000 ton force with the end product having dimensions generally 62 inches in width, 72 inches in length and 15 inches in depth with the radius of curvature in the curved peripheral wall portion being substantially 12 inches. After the intermediate product 34 has been formed, it is die cut by using a shaped die cutter either to cut the intermediate product lengthwise or crosswise into two end caps with the crosswise cut designated by broken line in FIG. 3 and indicated by reference numeral 36 defining the end edge 28. At the same time, the terminal edge of the curved periphery 36 is trimmed by a trimming die thus forming two end caps 22 from the single panel of sheet metal.

The metal pressing or stamping technique substantially reduces the time required to form a trailer end cap as compared with the welding of triangular segments or gores together and substantially reduces the time and labor required in forming an end cap for a trailer of this type as compared with a metal spinning technique. Moreover, the trailer end cap formed by employing the metal pressing or stamping technique produces a more uniform trailer end cap that is relatively rigid in construction and also enables variation in the shape, size and configuration of the end cap as compared with the spinning technique which is limited to a shape that is generated by revolving a panel of sheet metal about a rotational axis. For example, the overall front to rear length of the cap 22 as shown in FIG. 1 may vary between approximately 30 inches to 40 inches. Also, the trim line which forms the bottom edge of the edge portion 26 may be varied elevationally to vary the depth of the cap. The crosswise cut 36 may be varied as to its relation to the center line along the substantially straight side edge portions of the formed intermediate product shown in FIG. 3. Further, the thickness of metal can be varied within certain limits.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

I claim:

1. The method of forming a closure end cap between a vertical front end wall of a horse transporting trailer and a substantially horizontal roof of the trailer in which the roof is provided with a substantially flat top portion and downwardly curved side edge portions and the front end wall is provided with rearwardly extending and generally parallel side edge portions and a semi-cylindrical curved front portion consisting of the steps of pressforming a generally rectangular panel of sheet metal in a male and female die to form an intermediate product having a central substantially flat, semi-elliptical panel, downwardly curved peripheral edge portions of the same curvature as the downwardly curved side edges of the roof and having a lower edge conforming with the curvature of the upper edge of the front end wall and a laterally projecting flange integral with the bottom edge of the downwardly curved peripheral wall, trimming the projecting flange from the intermediate product along the peripheral edge of the downwardly curved peripheral wall, dividing the trimmed intermediate semi-elliptical product into two

identical pieces by die cutting the semi-elliptical flat panel and the downwardly curved peripheral wall with a single operation of a die cutter having a flat portion conforming with the transverse dimension of the flat panel and a radiused edge portion at each edge for conforming with the radius of curvature of the downwardly curving side walls of the intermediate product thereby providing two pieces having a substantially semi-elliptical flat panel having a straight edge at one end thereof and a downwardly curving radiused edge portion around the remainder of the periphery thereof with the radius of curvature of the downwardly curved peripheral portion not exceeding approximately twelve inches, and securing one of said pieces to the horse transporting trailer with the downwardly curved peripheral wall portion being secured to the upper edge of the front end wall of the trailer, the straight edge of the panel being secured to the forward edge of the roof of the trailer with the radius of curvature of the straight edge of the panel conforming with and secured with the downwardly curved side edges of the roof of the trailer.
